UNITED STATES PATENT OFFICE.

KNUT JONAS ELIAS HESSELMAN, OF SALTSJÖ-STORÄNGEN, STOCKHOLM, SWEDEN.

VAPORIZER FOR INTERNAL-COMBUSTION ENGINES.

1,117,845.

Specification of Letters Patent. Patented Nov. 17, 1914.

Application filed August 20, 1913. Serial No. 785,697.

To all whom it may concern:

Be it known that I, KNUT JONAS ELIAS HESSELMAN, a citizen of the Kingdom of Sweden, residing at Saltsjö - Storängen, Stockholm, Sweden, have invented new and useful Improvements in Vaporizers for Internal-Combustion Engines, of which the following is a specification.

This invention relates to an improvement 10 in the vaporizers described in my United States Patent No. 910,534.

The invention will be fully understood from the following description and claims when the same are read in connection with 15 the drawings, accompanying and forming part of this specification, in which:

Figure 1 is a longitudinal section of my improved vaporizer. Fig. 2 is a side elevation of the same.

20 Similar numerals of reference designate corresponding parts in both views of the drawings.

The fuel or oil passes through the channel 2 into the supply channel 3 from which 25 it flows through the narrow ports 4 of the vaporizer body 1 into pockets 5 provided in the vaporizer body. When the valve 6 is open the oil is carried by the air pressure through the channel 7 and into the cylinder.

In furtherance of my present invention each connecting channel or port 4 is formed with two enlarged portions 8. The number of such portions is, however, arbitrary. The 35 portion of each port 4 connecting the two enlarged portions 8 with each other should be wider than the portion of same port connecting the annular oil supply channel 3 and the enlarged portion 8 nearest to said 40 channel 3 in order that the oil may pass at a lower speed between the two enlarged channel portions than between the channel 3 and the enlarged channel portion nearest thereto. In using for instance three enlarged portions in each connecting port 4 the portion 45 between the last two enlarged port portions is made wider than between the first two enlarged port portions and so on. The portions of the ports 4 forming connecting passages may, as is shown in the drawing, be displaced in relation to each other so that the path of the oil becomes curved whereby the whirling motions of the oil will be increased.

50 By suitable choice of the number and size of the enlarged port portions and of the cross sectional area of the port portions between

the said enlarged portions one may reduce the speed of the oil in any desired degree, so that the oil settles quietly in the pockets 5 and is thereupon carried by the air through 60 the channels 7 in a reliable manner when the valve 6 is opened.

The vaporizers of my said Patent No. 910,534, dated January 26, 1909 have proved satisfactory in function when placed in 65 vertical or approximately vertical position, but they are not reliable when placed in horizontal or approximately horizontal position. This is due to the fact that oil introduced into the annular supply channel 3 70 tends on account of gravity to occupy the lowermost portion of said channel, and that to attain a uniform distribution of oil around the vaporizer body it is necessary to make the connecting ports very narrow in 75 order to obtain in the same a resistance that is sufficient to compel the oil to distribute itself uniformly in all of the connecting ports. The oil must, however, pass through the connecting ports with great rapidity. 80 This rapidity prevents the oil from settling quietly in the pockets, and it is therefore necessary to reduce the same to a material extent. To this end the connecting ports between the oil supply channel and the pockets 85 are as described formed with one, two or more enlarged portions in which the rapidity of motion of the oil will be reduced by friction and whirling motion so that the oil can settle quietly in the said pockets. 90

Having now described my invention, what I claim as new and desire to secure by Letters Patent is:

1. A vaporizer of the type described for internal combustion engines, comprising a 95 body having an oil-supply channel and oil-receiving means spaced from said channel and also having connecting channels extending directly between the oil-supply channel and the oil-receiving means; each of said 100 channels being provided with a comparatively large portion adjacent and connected with the oil-receiving means and a contracted portion between said large portion and the oil-supply channel. 105

2. A vaporizer of the type described for internal combustion engines, comprising a body having an oil-supply channel and oil-receiving means spaced from said channel and also having between said oil-supply 110 channel and oil-receiving means, connecting channels each of which is provided with

spaced enlarged portions, one of said portions being connected by a contracted portion with the oil-supply channel, and the two enlarged portions being connected together by a contracted portion larger than the first-named contracted portion.

In testimony that I claim the foregoing as

my invention, I have signed my name in presence of two subscribing witnesses.

KNUT JONAS ELIAS HESSELMAN.
